Michael Lax, 68 E. 91st St.,
New York, N.Y. 10028

Filed Mar. 8, 1974, Ser. No. 449,491

Term of patent 14 years

Int. Cl. D7—02

U.S. Cl. D7—60

FIG. 1 is a perspective view of my design for a tea kettle;

FIG. 2 is a side view of the tea kettle, the side opposite being a mirror image thereof;

FIG. 3 is a top plan view of the tea kettle;

FIG. 4 is a front view of the tea kettle;

FIG. 5 is a rear view of the tea kettle; and

FIG. 6 is the same view as FIG. 1 except that in this instance, the cap on the spout of the kettle is raised.

The bottom is substantially plain.

I claim:

The ornamental design for a tea kettle, substantially as shown and described.
